UNITED STATES PATENT OFFICE.

EDWARD R. VIVES, OF NEW YORK, N. Y., ASSIGNOR TO VESDAL CREATIONS, INC., OF NEW YORK, N. Y., A CORPORATION OF NEW YORK.

LOCK.

Application filed April 21, 1923. Serial No. 633,633.

To all whom it may concern:

Be it known that I, EDWARD R. VIVES, a subject of the King of Spain, and a resident of New York, in the county of New York and State of New York, have invented 5 certain new and useful Improvements in Locks, of which the following is a specification.

This invention relates to locks and particularly to combination locks of the multiple-key type.

The object of my present invention is to produce a lock of the above type in which the combination can be easily and quickly 10 changed, in which the number of possible combinations is practically unlimited, and in which the parts are comparatively few and easy to manufacture. A further object of this invention is to produce a lock 15 which has provisions for adjustment to doors of different thicknesses. Other objects and advantages of the invention will become apparent hereinafter.

Referring to the accompanying drawings, 20 which illustrate one practical physical embodiment of the invention:

Figure 1 is an inside elevation of a door provided with a lock constructed in accordance with my invention.

Figure 2 is a horizontal sectional view 25 through the lock, showing a suitable latch adapted to cooperate therewith.

Figure 3 is a vertical section through the lock and latch.

Figure 4 is a vertical sectional view of 30 the key operated bolt controlling mechanism, taken on the line 4—4 of Figure 2.

Figure 5 is a view similar to Figure 4, showing a key inserted.

Figure 6 is a face view of the key-hole 35 plate.

Figure 7 is a side view of one of the combination plugs.

Figure 8 is a transverse sectional view of 40 the plug.

Figure 9 is a perspective view of an adjusting plug adapted to form an extension of the combination plug.

Figure 1 shows an inside view of an 45 ordinary door having the lock of my invention applied thereto. The door has a rectangular recess cut in its inner face open inwardly and at the edge of the door. An open casing 10 is fitted in this recess and a cover plate 11 is secured flush with the inner 50

face of the door over the casing, the cover plate extending beyond the casing to form flanges through which the fastening devices securing the plate may pass. A bolt 12 is mounted in the casing and is adapted to 60 be projected and retracted through a slot therein, as usual. Secured to or formed with the body of bolt 10 is an open rectangular extension 13 which has a sliding fit with the upper and lower walls of the 65 casing. The end of this extension is spaced from the rear wall of the casing, and suitable springs 14 are interposed between the casing and bolt extension tending to project the bolt. Any suitable means may be 70 employed for retracting the bolt after the correct combination has been made by insertion of the proper key. The drawings illustrate for this purpose a cam arm 15 bearing against the inner side of the bolt 75 extension and secured to a transverse shaft 16 which projects on the outer side of the door and is there provided with a suitable handle or knob.

The bolt controlling mechanism is mounted in a flat rectangular member 17 which rests with its end side flush against the cover plate 11 and extends through a slot formed in casing 10 and a slot in the door registering therewith. The outer portion of 80 member 17 is slightly enlarged to form shoulders 18 which engage casing 10. The member 17 has machined therein a number of parallel bores 19 of equal diameter all located in the same vertical plane and extending completely through said member. Any desired number of bores may be employed, in so far as the scope of my invention is concerned. The drawings illustrate five such bores, which number will 85 probably be sufficient for all practical purposes. Five holes are formed in the cover plate 11. These holes, which are designated by the reference numeral 20, have the same diameter as that of the bores 19 and are located in registration therewith. Secured against the inside of cover plate 11 is a rectangular member 21, which has substantially the same dimensions as member 17, and is secured in alignment therewith. Member 21 has five cylindrical sockets 22 of the same diameter as that of bores 19 and holes 20 and located coaxially with said bores and holes. In each of the bores there is a combination plug 23, which may be of the 90 100 105 110

form illustrated by Figures 7 and 8. As shown, these plugs are cylindrical and have a number of parallel longitudinal grooves of V-section cut in their periphery. So far as the scope of the present invention is concerned, however, these grooves may have a U section or any other suitable section. Formed adjacent the outer end of each plug is an annular groove 25, which has a function that will be explained hereinafter.

For the purpose of adapting the lock to doors of different thicknesses, it is proposed to furnish with each lock a number of short plugs 26, such as illustrated by Fig. 9. Each of these small plugs have a threaded pin projecting from one end and a threaded hole tapped into its other end. The threaded pin is adapted to screw into a hole tapped into the end of grooved plug 23 or into a hole of another small plug. Thus the grooved plugs may be extended by fastening on to the outer ends thereof one or more of these small plugs. In Fig. 2 the plugs 23 are shown extended by one small plug. In the case of a thicker door, two or more plugs might be found necessary to extend to the outer side of the door, and where the door is thin enough to bring the outer end of a grooved plug 23 flush with the outer face of the door, no auxiliary plugs will be necessary. In each of the sockets 22 there is a coil spring 27 which bears against the inner end of the plug and normally holds it against the inner face of the key hole plate 28. The key-hole plate is provided with five apertures for insertion of the key prongs, these apertures being located coaxially with bores 19 and sockets 22.

In the embodiment of the invention illustrated, each plug 23 has nine grooves and nine diametrical holes. These diametrical holes each open at one end centrally of a groove, opening at the other end partly in one groove and partly in the adjacent groove. This is shown in Fig. 8, wherein the diametrical hole opens at one end 29 centrally of a groove and at its other end 30 partly in two grooves. The diametrical holes are arranged spirally around the plug, as illustrated by Fig. 7.

Formed in member 17 are five transverse apertures or holes 31, which are located in the same vertical plane and which intersect the centers of bores 19. Projecting from the rear face of bolt 12 are five pins 32 which are located in alignment with the holes 31 and project thereinto. Obviously the bolt cannot be retracted unless the combination plugs 23 are in such positions that, in each of said plugs, a diametrical hole thereof is in alignment with its associated pin 32. Then, and then only, can the pins 32 pass through the plugs and the bolt be retracted.

The combination of the lock depends upon the positions of the diametrical holes in the grooved plugs relatively to the pins 32 and, therefore, on the distances these plugs have to be pushed in by the key prongs in order to bring the diametrical holes therein in alignment with the pins.

Projecting inwardly from the periphery of each of the holes 20 in cover plate 11 there is a tooth 33 located in the horizontal plane passing through its associated pin 32, this tooth being adapted to fit in the grooves 24 of the plug and thus lock the latter against rotational movement while permitting it to be reciprocated longitudinally. Hence the tooth engaging in a groove of the plug holds the plug in a fixed rotational position with the associated pin 32 pointing to the center of the groove engaged by the tooth. Since each groove has only one diametrical hole opening centrally thereof, it is clear that for a given rotational position of the plug there is only one longitudinal position thereof where the associated pin can pass therethrough, viz., that position where the hole which opens centrally in that groove which tooth 33 engages is in alignment with the pin. If the plug is brought to a longitudinal position wherein the associated pin is opposite holes which open only partly in the groove, the pin cannot pass. In order that for a given rotational position of the plug there may not be more than one longitudinal position where the associated pin can pass, the number of grooves in the plug should be odd, for a plug having an even number of grooves would have the diametrical holes thereof opening centrally of two diametrically opposite grooves, and therefore for each plug there would be two longitudinal positions thereof, for each of its nine rotational positions, in which the associated pin could pass.

The combination of the lock, as heretofore stated, depends upon the positions of the diametrical holes in the combination plugs relatively to the pins 32. Therefore, in order to change the combination, it is only necessary to rotate one plug through an angle of one groove, thus bringing the next groove opposite the associated pin. This would change the combination, since the diametrical hole of said next groove is located at a different position with respect to said pin, requiring the plug to be moved longitudinally a different distance in order to bring the hole in alignment with the pin. Since there are five plugs and nine rotational positions of each plug, it will be readily appreciated that the number of possible combinations is very great.

In order to permit the plugs to be set in different rotational positions in the bores without necessitating the disassembling of

the lock, each plug has formed adjacent its outer end the annular groove, 25, previously referred to. Hence when the member 21 has been removed, the plugs may be rotated to new positions by withdrawing them inwardly until the grooves 25 are opposite the teeth 33, whereupon they may be rotated to any desired positions and then pushed into the bores with the teeth 33 engaging the selected grooves. The member 21 is secured by headed cylindrical nuts 34, which are screwed on the projecting ends of threaded bolts attached to the key hole plate 28 and projecting through the casing 10, 15 11 and through holes in end flanges 36 formed on member 21. The member 21, therefore, is removed simply by unscrewing the nuts 34.

Latch mechanism operable from inside 20 the door is provided to coact with the bolt mechanism above described. The latch illustrated is mounted in a casing 37 which is secured in a recess in the jamb of the door. It consists of a body portion 38 slide- 25 able vertically in casing 27 and formed with upwardly projecting bolt engaging members 39 and 40. A coil spring 41, bearing at one end against the bottom of casing 37 and at its other end against the top of a recess 30 formed in the underside of body 28, yield- ingly holds the latch in its upper or normal position. The upward movement of the latch is limited by a horizontal plate formed integrally with the face plate of casing 27 35 and engaging the latch between the members 39 and 40. The outer face of member 40 has a cam formation so that the latch will be cammed downwardly by bolt 10 when the door is shut. The door can be opened 40 from the inside by manipulating a knurled head having a shank attached to member 40 and projecting through a vertical slot in casing 37. The door can thus be opened from the inside by any one, but can only be 45 opened from the outside by a key corresponding to the particular combination for which the lock is set.

Now having particularly described one embodiment of my invention without, however, intending to limit the scope of the invention to the specific structure disclosed, what I claim as new and desire to secure by Letters Patent of the United States is:—

55 1. In a lock, the combination with the bolt, of controlling mechanism therefor comprising a plurality of plugs mounted to reciprocate longitudinally in paths transverse to said bolt, said bolt having a plurality of pins projecting in lines which intersect said plugs, each of said plugs having a plurality of holes adapted to be brought into alignment with said pins, said holes being longitudinally and circumferentially spaced along said plug, means for fixing each of

said plugs in a plurality of rotational positions to bring any selected hole thereof into cooperation with its associated pin, and springs holding said plugs in normal longitudinal positions. 70

2. In a lock, the combination with the bolt, of controlling mechanism therefor comprising a plurality of plugs mounted to reciprocate longitudinally in paths transverse to said bolt, said bolt having a plurality of pins projecting in lines which intersect said plugs, each of said plugs having a plurality of holes adapted to be brought into alignment with said pins, said holes being longitudinally and circumferentially spaced along said plug, means for fixing each of said plugs in a plurality of rotational positions to bring any selected hole thereof into cooperation with its associated pin, said plugs being biased to normally assume a 85 definite position. 75

3. In a lock, the combination with the bolt, of controlling mechanism therefor comprising a plurality of plugs mounted to reciprocate in paths transverse to said bolt, said bolt having a plurality of pins projecting in lines which intersect the longitudinal axes of said plugs, each of said plugs having a plurality of holes passing diametrically therethrough and adapted to be 90 brought into alignment with said pins, said holes being arranged spirally around said plug, means for fixing said plugs in a plurality of rotational positions to bring any 95 selected hole thereof into cooperation with its associated pin, said plugs being biased to assume a definite normal position, and a key having a plurality of prongs adapted to move said plugs longitudinally to bring the holes thereof into alignment with said 100 pins to permit retraction of the bolt. 105

4. In a lock, the combination with the bolt, of controlling mechanism therefor comprising a plurality of plugs mounted to reciprocate in paths transverse to said bolt, 110 said bolt having a plurality of pins projecting in lines which intersect the longitudinal axes of said plugs, each of said plugs having an odd number of parallel longitudinal grooves and having diametrical holes adapted to be brought into alignment with said pins, each of said holes opening at one end centrally in a groove and at its other end partly in adjacent grooves, each groove having only one hole opening centrally therein and said grooves being arranged spirally around said plug, means for fixing said 115 plugs in a number of rotational positions corresponding to the number of grooves therein to bring any selected hole thereof into cooperation with the associated pin, said plugs being biased to assume a definite normal position, and a key having a plurality of prongs adapted to move said plugs longitudinally to bring the holes thereof 120 125 130

into alignment with said pins to permit retraction of the bolt.

5. A lock comprising a flat rectangular casing having a front plate provided with an opening, a bolt reciprocably mounted in said casing projecting through said opening, said bolt having an open rectangular extension in said casing, a spring between the end of said extension and the end wall of said 10 casing tending to project said bolt, a flat rectangular block extending through said casing at right angles to said bolt and embraced by said rectangular extension, said block projecting on the outer side of said 15 casing and extending flush against the inner wall of the inner side of said casing, said block having a plurality of parallel bores extending completely therethrough and said inner plate of the casing having a plurality 20 of holes registering with said bores, a block removably secured to the outside of said inner plate having a plurality of sockets registering with said holes, a key hole plate secured against the outer end of said first 25 mentioned block having a plurality of holes communicating with said bores, a plug in each bore having an odd number of peripheral parallel longitudinal grooves, said plug having a corresponding number of diametrical holes, there being one and only one hole opening centrally in each groove and said holes being longitudinally spaced along 30 said plug, springs in said sockets normally holding said plugs against said key-hole plate, said block having transverse apertures intersecting the centers of said bores, a plurality of pins fixed to said bolt and projecting in alignment with said apertures, means for fixing said plugs in a plurality of rotational positions to bring selected holes thereof into cooperation with said pins, a key having a plurality of pins adapted to be inserted through said key-hole plate to move said plugs.

45. 6. A lock comprising a flat rectangular casing having a front plate provided with an opening, a bolt reciprocably mounted in said casing projecting through said opening, a flat rectangular block extending 50 through said casing at right angles to said bolt, said block projecting on the outer side of said casing and extending flush against the inner wall of the inner side of said casing, said block having a plurality of parallel bores extending completely therethrough and said inner plate of the casing having a plurality of holes registering with said bores, a block removably secured to the outside of said inner plate having a plurality of sockets registering with said holes, a plug in each 55 bore having a plurality of holes communicating with said bores, a key hole plate secured against the outer end of said first mentioned block having a plurality of holes 60 communicating with said bores, a plug in each bore having a plurality of diametrical holes circumferential-

tially and longitudinally spaced, springs in said sockets normally holding said plugs against said key-hole plate, said block having transverse apertures intersecting the centers of said bores, a plurality of pins fixed to said bolt and projecting in alignment with said apertures, means for fixing said plugs in a plurality of rotational positions to bring selected holes thereof parallel to said apertures, and a key having a plurality of pins adapted to be inserted through said key-hole plate to move said plugs.

7. A lock comprising a casing provided with an opening, a bolt reciprocably mounted in said casing projecting through said opening, a block extending through said casing at right angles to said bolt, said block projecting on the outer side of said casing and extending flush against the inner wall of the inner side of said casing, said block having a plurality of parallel bores extending completely therethrough and said inner plate of the casing having a plurality of holes registering with said bores, a block removably secured to the outside of said inner plate having a plurality of sockets registering with said holes, a key hole plate secured against the outer end of said first mentioned block having a plurality of holes communicating with said bores, a plug in each bore having a plurality of diametrical holes circumferentially and longitudinally spaced, springs in said sockets holding said plugs against said key-hole plate, said block having transverse apertures intersecting the centers of said bores, a plurality of pins fixed to said bolt and projecting in alignment with said apertures, means for fixing said plugs in a plurality of rotational positions to bring selected holes thereof parallel to said apertures, and a key having a plurality of pins adapted to be inserted through said key-hole plate to move said plugs.

8. A lock comprising a casing provided with an opening, a bolt reciprocably mounted in said casing projecting through said opening, a block extending through said casing transverse to said bolt, said block projecting on the outer side of said casing and extending flush against the inner wall of the inner side of said casing, said block having a plurality of parallel holes extending completely therethrough and the inner plate of the casing having a plurality of apertures registering with said holes, a plug in each of said holes comprising a main portion having a plurality of diametrical holes circumferentially and longitudinally spaced and a relatively short detachable portion, a key-hole plate adapted to be secured against the outer face of the closure to which the lock is applied having a plurality of holes adapted to communicate with the holes in said block, a second block having a plurality of sockets registering with the apertures in

- said inner plate, springs in said sockets holding said plugs against said key-hole plate, said first mentioned block having transverse apertures intersecting the axes of the holes 5 therein, a plurality of pins fixed to said bolt and projecting in alignment with said transverse apertures, means for fixing said plugs in a plurality of rotational positions to bring selected holes thereof parallel to said transverse apertures, and a key having a plurality of pins adapted to be inserted through said key-hole plate to move said plugs. 10
9. A lock comprising a casing provided with an opening, a bolt reciprocably mounted 15 in said casing projecting through said opening, a block extending into said casing transverse to said bolt, said block projecting on the outer side of said casing and having a plurality of parallel holes transverse to said casing, a plug in each of said holes comprising a main portion having a plurality of diametrical holes circumferentially and longitudinally spaced and a relatively short detachable portion, a key-hole plate adapted 20 to be secured against the outer face of the closure to which the lock is applied having a plurality of holes communicating with the holes in said block, resilient means for holding said plugs against said key-hole plate, 25 said block having transverse apertures intersecting the holes therein, a plurality of pins fixed to said bolt and projecting in alignment with said apertures, means for fixing said plugs in a plurality of rotational 30 positions to bring selected holes thereof parallel to said apertures, and a key having a plurality of pins adapted to be inserted through said key-hole plate to move said plugs. 35
10. A lock comprising a casing provided with an opening, a bolt reciprocably mounted 40 in said casing projecting through said opening, a block extending into said casing transverse to said bolt, said block projecting on the outer side of said casing and having a plurality of holes extending transversely to said bolt, a plug in each of said holes having a plurality of transverse holes circumferentially and longitudinally spaced, a key hole plate adapted to be secured 45 against the outer face of the closure to which the lock is applied having a plurality of holes communicating with the holes of said block, said plugs being biased to rest normally against said key-hole plate, said 50 block having transverse apertures intersecting the holes therein, a plurality of pins fixed to said bolt projecting in alignment with said apertures, means for fixing said plugs in a plurality of rotational positions to bring selected holes thereof parallel to 55 said apertures, and a key having a plurality of pins adapted to be inserted through said key-hole plate to move said plugs. 60
11. A lock comprising a casing provided 65 with an opening, a bolt reciprocably mounted in said casing projecting through said opening, a block extending into said casing transverse to said bolt, said block projecting on the outer side of said casing and having a plurality of parallel holes extending transversely to said bolt, a plug in each of said holes having a plurality of diametrical holes circumferentially and longitudinally spaced, a key-hole plate adapted to be secured 70 against the outer face of the closure to which the lock is applied having a plurality of holes communicating with the holes of said block, said plugs being biased to rest normally against said key-hole plate, said 75 block having transverse apertures intersecting the holes therein, a plurality of pins fixed to said bolt projecting in alignment with said apertures, means for fixing said plugs in a plurality of rotational positions to bring selected holes thereof parallel to said apertures, and a key having a plurality of pins adapted to be inserted through said key-hole plate to move said plugs. 80
12. A lock comprising a casing provided with an opening, a bolt reciprocably mounted 85 in said casing projecting through said opening, a block extending into said casing transverse to said bolt, said block projecting on the outer side of said casing and having a plurality of holes extending transversely to said bolt, a plug in each of said holes having a plurality of transverse holes circumferentially and longitudinally spaced, a key hole plate adapted to be secured 90 against the outer face of the closure to which the lock is applied having a plurality of holes communicating with the holes of said block, said plugs being biased to rest normally against said key-hole plate, said 95 block having transverse apertures intersecting the holes therein, a plurality of pins fixed to said bolt projecting in alignment with said apertures, means for fixing said plugs in a plurality of rotational positions to bring selected holes thereof parallel to said apertures, and a key having a plurality of pins adapted to be inserted through said key-hole plate to move said plugs. 100
13. In a lock, the combination with the bolt of controlling mechanism therefor comprising a plurality of elongated members mounted to reciprocate longitudinally in paths transverse to said bolt, said bolt having a plurality of pins projecting in lines 115 which intersect said members, each of said members being constructed to permit the passage of its associated pin only in certain longitudinal and rotational or angular positions thereof, and means for fixing each of said members in a plurality of angular positions, said members being biased to assume definite normal longitudinal positions. 120
14. In a lock, the combination with the bolt of controlling mechanism therefor comprising a plurality of elongated members mounted to reciprocate longitudinally in paths transverse to said bolt, said bolt having a plurality of pins projecting in lines 125 which intersect said members, each of said members being constructed to permit the passage of its associated pin only in certain longitudinal and rotational or angular positions thereof, and means for fixing each of said members in a plurality of angular positions, said members being biased to assume definite normal longitudinal positions. 125
